UNITED STATES PATENT OFFICE.

EDWIN E. OVERHOLT, OF WASHINGTON, DISTRICT OF COLUMBIA.

COMPRESSED-AIR CARPET-CLEANER.

1,005,290.

Specification of Letters Patent. Patented Oct. 10, 1911.

Original application filed May 24, 1902, Serial No. 108,815. Divided and this application filed September 11, 1905. Serial No. 278,010.

To all whom it may concern:

Be it known that I, EDWIN E. OVERHOLT, citizen of the United States, residing at Washington, in the District of Columbia, have invented new and useful Improvements in Compressed - Air Carpet - Cleaners, of which the following is a specification.

My invention relates to compressed air carpet cleaners, being a division of application Serial No. 108,815 dated May 24, 1902.

My object is to provide a machine for cleaning carpets on the floor which will readily remove dust from underneath the carpet as well as from the top thereof, thereby cleaning not only the carpet but also the floor; which will be unusually light for handling: and which will do the required work with a minimum expenditure of air.

In the accompanying drawings, Figure 1 is a vertical transverse section of Fig. 2 taken on the line 1—1 of Fig. 2. Fig. 2 is a plan view showing the bottom of the device. Fig. 3 is a plan view of the pressure-equalizing plate, and; Fig. 4 is a sectional view of the nozzle on an enlarged scale, showing the means of securing the same to the body of the device, and of adjusting it relatively thereto.

The numeral 1 designates the body of my device, having on its top side an air chamber divided into upper and lower compartments 2 and 3 respectively by the longitudinally extending plate 4. The compartment 2 communicates with a pipe 5 which is connected with a source of supply of compressed air. The plate 4 is supported in position by screws 6.

On the under side of the body 1 is a downwardly extending nozzle 7, surrounded by the downwardly extending continuous flanges 8 and 9. These flanges extend to the working plane of the body 1, and are adapted to rest upon the top of the carpet; while the nozzle 7 projects beyond said plane to be forcibly pressed into the pile of the carpet, and to be deeply embedded therein. By this arrangement a great part of the weight of the device is borne by the nozzle, care being taken that the flanges 8 and 9 shall not project below the working plane of the device, as that would cause said flanges to support a perceptible part of the weight of the device, and would by that much lighten the pressure upon the nozzle 7, which is not desirable.

The nozzle is secured to the body 1 by means of screws or bolts as illustrated in Fig. 4; and between the nozzle 7 and said member may be interposed, from time to time, one or more strips of thin material 10 to increase the projection of the nozzle to compensate for wear on the working face thereof, and to adapt the nozzle for use on carpets having pile of more than the ordinary depth. The nozzle has a central outlet 11 and the width of this outlet may be regulated by the screws 12.

When the device rests upon the surface of a carpet the flanges 8 and 9 form chambers surrounding the nozzle with one chamber surrounding the other chamber. The chambers underneath the machine are adapted to be put into communication with each other when desired by means of the conical openings 13 in the flanges. These openings receive the plugs 14 when it is desired to cut off communication between said chambers. The body 1 is provided with similar openings and plugs 15 and 16 respectively. A suitable curved rod or bar 17 is secured to the top of the body 1 and supports a dust hood. The equalizing plate 4 has apertures for the passage of air from the chamber 2 into the chamber 3. These apertures are smallest at the point opposite the air inlet 85 where the pressure of air is the greatest, and they gradually increase in size toward the ends of the plate toward which the pressure gradually becomes less, thereby serving to equalize the air pressure throughout the 90 entire length of the chamber 3 and of the slit 11 leading therefrom through the nozzle.

In operation, the body 1 rests flat upon the carpet with sufficient pressure only to prevent the dust-laden air from escaping 95 around the sides 18 thereof, the nozzle being arranged to project sufficiently to support the rest of the weight of the device; so that the nozzle is pressed forcibly upon the pile of the carpet, and by reason of such pressure is deeply embedded therein. Hence it will be seen that that portion of the carpet which is being acted upon at any given instant—namely, the portion immediately beneath the nozzle—is literally compressed between the nozzle and the floor, so that the blast of air is delivered, not upon loose pile—or fabric—but upon compressed pile. Moreover, the air delivered under pressure is thereby not only delivered deep down in 110

the pile of the carpet in position to most advantageously act upon the same, but is also delivered so close to the floor, that a goodly portion thereof passes through the carpet and strikes the floor with great force, and rebounds up through the carpet on either side of the nozzle, carrying up with it the dust from underneath the carpet.

If the apertures 13 are closed the air will 10 be compelled to dive under the flanges 8 and 9 into the pile of the carpet and finally escape around the edges 18 of the body member. If the plugs 14 are removed the air will not have to pass under the flanges in 15 order to escape: and if the plugs 16 are removed the dust laden air will escape upwardly into the hood.

Having thus described my invention what I claim as new and desire to secure by Letters Patent is:

1. A compressed air carpet cleaner comprising a body having an opening; and a nozzle arranged to project through said opening beyond the working face of said body.

2. A compressed air carpet cleaner comprising a body having an opening; and a nozzle rigidly connected to said body, and extending through said opening to a point 30 below the working face of said body.

3. A compressed air carpet cleaner comprising a body having a chamber on its under side, and a working face surrounding said chamber and adapted to rest on the carpet; and a delivery nozzle also provided with a working face adapted to engage the carpet, said face being flat and disposed in a plane parallel with the working face of the body of the device, said nozzle being 35 located in said chamber at a point spaced from the front and rear sides thereof and thereby adapted to engage a portion of the carpet spaced on both its front and rear sides from the portion engaged by the working face of the body of the device, said nozzle being arranged to project below said working face of the body of the device to continuously and forcibly press said spaced portion of the carpet, and having its outlet

40 at a point between the front and rear sides of the working face of the nozzle, whereby the blast from the nozzle is delivered into said compressed portion of the carpet at a point between the margins of said compressed portion, and not at one side or the other thereof.

4. A compressed air carpet cleaner comprising a body having a chamber on its under side, and a working face surrounding said chamber and adapted to rest on the carpet; and a delivery nozzle also provided with a working face adapted to engage the carpet, said face being flat and disposed in a plane parallel with the working face of the body of the device, said

nozzle being located wholly within said chamber at a point spaced from the front and rear sides thereof and thereby adapted to engage a portion of the carpet spaced on both its front and rear sides from the portion engaged by the working face of the body of the device, said nozzle being arranged to project materially below said working face of the body of the device to continuously and forcibly compress between the nozzle and the floor said spaced portion of the carpet, and having its outlet opening in an approximately vertical direction at a point between the front and rear sides of the working face of the nozzle; whereby the blast from the nozzle is delivered in a vertical direction into said compressed portion of the carpet at a point between the margins of said compressed portion, and not at an angle at one side or the other thereof.

5. In compressed air carpet cleaners, a body adapted to rest upon the carpet and provided with a plurality of chambers on its under side, one surrounding another; 90 and a nozzle operating within the inner one of said chambers, and spaced from the front and rear sides thereof.

6. A compressed air carpet cleaner comprising a body adapted to rest on the carpet and provided on its under side with an inner chamber and an outer chamber having independent dust outlets, and being arranged for communication with the inner chamber; a nozzle located within the inner chamber at a point spaced from the front and rear sides thereof; and means for controlling communication between said chambers as may be desired.

7. In compressed air carpet cleaners, a body adapted to rest upon the carpet and provided with chambers on its under side, and having openings leading up through said body from its under side; means for controlling said openings as may be desired, and a blast nozzle in the central one of said chambers.

8. A compressed air carpet cleaner having an elongated air chamber and an elongated opening leading therefrom for the delivery 115 of compressed air to the work, said chamber having a single inlet opening for conveying the compressed air thereinto; and means inside said chamber, located between the single inlet thereto and the outlet therefrom, for equalizing the air pressure at all points in said elongated outlet.

9. A compressed air carpet cleaner having an elongated air chamber and an elongated opening leading therefrom for the 125 delivery of compressed air to the work, said elongated chamber having a single inlet, opening approximately central thereof, for conveying the compressed air thereinto; and a distributing plate inside said chamber be- 130

tween the single inlet leading directly thereinto and the outlet leading therefrom, said plate being provided with graduated openings for equalizing the air pressure at all points in said elongated outlet.

5 10. A compressed air carpet cleaner comprising a body having a working face; a nozzle arranged to project beyond the working face of said body; and means for chang-

ing the distance the nozzle is arranged to project.

In testimony whereof I affix my signature, in presence of two subscribing witnesses.
